COMBINED SCRAPING AND CLEANING
IMPLEMENT OR SIMILAR ARTICLE

Fred Siegel, New York, N. Y.

Application March 3, 1948, Serial No. 144,891

Term of patent 3½ years

(Cl. D9—2)

To all whom it may concern:

Be it known that I, Fred Siegel, a citizen of the United States of America, residing in the city, county, and State of New York, have invented a new, original and ornamental Design for a Combined Scraping and Cleaning Implement or Similar Article, of which the following is a specification, reference being had to the accompanying drawing, forming a part thereof.

Fig. 1 is a perspective view of a combined scraping and cleaning implement showing my new design;

Fig. 2 is a front elevational view thereof, the handle fragmented for convenience of illustration; and

Fig. 3 is a side view thereof, the handle fragmented for convenience of illustration.

I claim:

The ornamental design for a combined scraping and cleaning implement or similar article, as shown.

FRED SIEGEL.
